UNITED STATES PATENT OFFICE.

JAMES F. LONG, OF SAN FRANCISCO, CALIFORNIA.

FOLDING CAMPING DEVICE.

1,351,178.

Specification of Letters Patent. Patented Aug. 31, 1920.

Application filed August 29, 1919. Serial No. 321,243.

To all whom it may concern:

Be it known that I, JAMES F. LONG, a citizen of the United States, residing in the city and county of San Francisco and State of California, have invented certain new and useful Improvements in Folding Camping Devices, of which the following is a specification.

My invention relates to improvements in folding camping devices for attachment to the rear end of a motor vehicle or the like wherein a bed operates in conjunction with the slats thereof to form a crate for bed clothing and other baggage when folded into an upright or inoperative position.

The primary object of the present invention is to provide an improved folding camping bed for attachment to motor vehicles.

A further object of the invention is to provide an improved device of the character described which may be easily and readily operated.

It is also an object to provide an improved device of the character described which shall be adapted for attachment to a motor vehicle without altering said vehicle.

I accomplish these several features by means of the improved device disclosed in the accompanying drawings forming a part of the present specification wherein like characters of reference are used to designate similar parts throughout the said specification and drawings, and in which:

Figure 1 is an elevation of the rear portion of a motor vehicle disclosing my device attached thereto in an extended or operative position;

Fig. 2 is a plan view of Fig. 1 with the top of the vehicle removed;

Fig. 3 is a view similar to Fig. 1 but with the device in folded or inoperative position;

Fig. 4 is a rear end elevation of Fig. 3;

Fig. 5 is an enlarged broken detailed view of the locking means; and

Fig. 6 is a right hand elevation of Fig. 5.

Referring to the drawings the numeral 1 is used to designate the rear end of a motor vehicle having the usual bolt 2 for the support of the top bows 3 and the bracket 4 for supporting said bows 3 in lowered position.

Secured to the bolts 3 and brackets 4 on both sides of the vehicle 1, I have provided the angle irons 6 arranged to support a trans-

verse angle 7 from which depends a pair of

vertically disposed supporting frames 8, said frames 8 being further supported at their lower ends by means of a second transverse angle 9 in turn supported by angle braces 11 which have their upper or opposite ends secured to the angle irons 6 and adjacent the bolts 2.

Pivottally mounted at one of their ends to the lower ends of the supporting frames 8 are stringers 12 which constitute the bed frame of the device. This bed frame 12 is provided with legs 14 and braces 16 to support the bed frame 12 when lowered to a horizontal position for use and when in such position said frame 12 extends horizontally from the pivotal points by means of which it is connected to the lower ends of the supporting frame 8. A receptacle 17 for the reception of baggage, groceries and other material, is pivotally suspended between the braces 16 and is provided with two apertured extensions 18 which extend horizontally from the lower front edge of the receptacle 17. Parallel movement bars 19 are pivotally connected to the supporting frame 8 and to the upper ends of the receptacle 17 whereby said receptacle 17 may be retained in a horizontal position when the bed frame 12 is lowered as disclosed in Fig. 1 of the drawings.

A U-shaped crate, comprising hingedly connected slatted sections 21, 22 and 23, is mounted upon the frame 12, the central section resting upon or across the legs 14 of the bed frame 12 when in a vertical position as disclosed in Figs. 3 of the drawings. The battens 24 of the outermost section 21 extend downwardly and through the apertures of the extensions 18 of the receptacle 17 to retain said section in a vertical position and the battens 26 of the central section 22 are provided with apertured lateral extensions 27 which are secured to the supporting frame 8 by means of suitable bolts and thumb nuts 28, the innermost slat of the section 22 impinging against the vertically positioned bed frame 12 to retain said frame 12 against the transverse angle 7 and in an upright position. The transverse angle iron 7 is provided with two latches 31 adapted for engagement with the flanges of the bed frame 12 to retain said frame 12 in an upright position, when the sections 21, 22 and 23 are removed in a manner hereinafter more fully set forth.

The battens 24 of the section 21 are pro-

vided with lugs 32 which engage the under sides of the ends of the legs 14 to prevent removal of said section and to retain the same in position.

5 A table, 33, having legs 34 on one side only thereof, and a depending frame 36 on the side opposite said legs 34, is pivotally mounted by means of said legs 34 to the foot end of the bed frame 12 and at a distance slightly below the tops of said legs, 10 said table top 33 extending over the U-shaped crate sections, which form a compartment for the reception of baggage and the like, when the device is folded as disclosed in Fig. 3 of the drawings, and extending slightly above the bed frame 12 when in a lower or horizontal position, as disclosed in Fig. 1 of the drawings.

From the frame 36 of the table 33 is pivotally suspended a second frame or bar 37 the lower end of which rests against the inside of the crate section 21 which section thereby prevents said frame or bar 37 from swinging outwardly and thereby forms a 25 complete compartment for the storage of baggage and the like.

When the bed frame is lowered as disclosed in Fig. 1 of the drawings this frame 37 may be swung upwardly to a vertical position to serve as a support for a suitable shelter, as disclosed in dotted lines in said figure.

The table is rigidly secured in this position by means of a suitable detachable brace 35 39 which is secured to the bed frame 12.

To lower the device to an operative position the thumb nuts 28 are first removed and the crate sections 21, 22 and 23 are then removed by moving the upper end of the 40 section 21 outwardly to clear the lugs 32 from the under surfaces of the legs 14 and then lifted to remove the battens 24 thereof from the apertured extensions 18 of the receptacle 17 and the entire three sections are 45 then removed bodily from the device and set temporarily aside.

The bed frame 12 is then released from the supporting frames 8 by releasing the latches 31 and said bed frame is then lowered on its pivotal points to a horizontal position. The table top 33 is then adjusted to form a support for the foot or outermost end of the bed frame 12 and the brace 39 is secured in position. This leaves the table 50 top 33 above the plane of the bed frame 12. The crate sections are then laid across the bed frame stringers 12 to serve as a support for the seat cushions 41 of the vehicle 1 as disclosed in dotted lines in Fig. 1 of the drawings, with the section 23 resting inclined upon the parallel movement bars 19 as disclosed. This inclined section 23 is 55 hingedly connected to the adjacent section 22 in such a manner that said section 23 rests slightly above the section 22 thereby

serving as a support for cushions or pillows 42 also indicated in dotted lines in Fig. 1 of the drawings.

Having thus described my invention what I claim as new and desire to secure by Letters Patent is:

1. A folding camping device comprising a frame arranged to be attached to the rear of a motor vehicle or the like; vertically disposed stringers pivotally mounted at their lower ends to the frame and arranged to be lowered to extend horizontally from said pivotal points; suitable legs secured to the stringers; braces between said legs and stringers; a receptacle pivotally mounted between said braces; means for maintaining the receptacle in an upright position; a table portion pivotally mounted upon the upper ends of the stringers and having legs on one side of said table whereby the top 85 of said table will extend above the top of the stringers when lowered to a horizontal position; and a U-shaped crate comprising three sections hingedly connected, one vertical section of said crate having depending legs to engage the bottom of the receptacle, and the horizontal or central section of said crate being adapted for locking engagement with the frame to hold the stringers in a vertical or folded position. 95

2. A folding camping device comprising a pivotally mounted bed frame adapted for a folded vertical and inoperative position and a horizontally extended operative position; suitable legs for supporting the frame in an operative position; a table pivotally connected to the foot of the bed frame and arranged to form a cover spaced above said frame in a folded position, and a foot support and table arranged slightly above the bed frame when in an operative position; and a U-shaped crate adapted to form slats for the bed frame when in operative position for locking said bed frame in a folded or inoperative position. 110

3. A folding camping device comprising a supporting frame adapted for attachment to the rear of a motor vehicle or the like; a vertically disposed bed frame pivotally mounted at its lower end to the lower end of the supporting frame and adapted for horizontal extension from said pivotal points; a receptacle pivotally mounted below the bed frame and having apertured horizontal extensions opposite the bed frame; a parallel movement bar pivotally connected to the supporting frame and the receptacle to retain said receptacle in a horizontal position when the bed frame is lowered, said bar operating as a head rest support when the bed frame is lowered; a U-shaped crate comprising three hingedly connected sections, one of said sections being provided with extended legs to engage the apertures in the horizontal extensions 130

of the bed frame, and the central section of said crate being adapted for engagement with the supporting frame and to hold the bed frame in vertical position; and a table 5 pivotally connected to the upper end of the bed frame to form a cover for the crate, said table being adapted to project above the bed frame when lowered to form a foot support; and a depending frame pivotally 10 mounted upon one side of said table to form a support for a shelter or the like.

4. In a folding camping device the combination of a vertically disposed supporting frame adapted for engagement with the 15 rear end of a motor vehicle or the like; a vertically disposed bed frame pivotally mounted at the head or lower end thereof with the lower end of said supporting frame whereby said bed frame may be lowered to a horizontal position; suitable legs 20 on the bed frame; a receptacle pivotally mounted between the legs of the bed frame and having horizontally extended apertured extensions on the lower edge thereof 25 and opposite the bed frame when vertical; a parallel movement bar pivotally connected to the supporting frame and to the receptacle to retain said receptacle in a horizontal position when said bed frame is lowered; a U-shaped crate comprising three 30 hingedly connected sections arranged with the center horizontal section resting on the legs of the bed frame and adapted for engagement with the bed frame and locking engagement with the supporting frame to lock said bed frame in vertical and folded 35 position, and the remaining vertical section being positioned against the bed and supporting frames, said U-shaped crate being also adapted to lie upon the bed frame when lowered to provide supporting slats for seat 40 cushions or the like, with the last mentioned section resting inclined upon the parallel movement bar to serve as a head support for pillows and the like; a table having legs on one side only thereof, said legs being pivotally connected to the upper end and foot of the bed frame whereby the top of 45 said table may project above the bed frame when lowered to form a foot rest and table, said table top forming a cover for the crate when the device is in a folded position; and a support pivotally mounted upon the table 50 on the side opposite the legs, said support depending against the inside of the first mentioned crate section thereby forming a compartment with said crate to receive baggage, and adapted to project above the table 55 top when the bed is lowered to form a support for a shelter or the like.

5. In a folding camping device the combination of a vertically disposed supporting frame adapted for engagement with the rear end of a motor vehicle or the like; a vertically disposed bed frame pivotally mounted at the head or lower end thereof with the lower end of said supporting frame whereby said bed frame may be lowered to a horizontal position; suitable legs on the bed frame; a receptacle pivotally mounted between the legs of the bed frame and having horizontally extended apertured 60 extensions on the lower edge thereof and opposite the bed frame when vertical; a parallel movement bar pivotally connected to the supporting frame and to the receptacle to retain said receptacle in a horizontal position when said bed frame is lowered; a U-shaped crate comprising three hingedly connected sections arranged with the center horizontal section resting on the legs of the bed frame and adapted for engagement with the bed frame and locking engagement with the supporting frame to lock said bed frame in vertical and folded 65 position, and the remaining vertical section being positioned against the bed and supporting frames, said U-shaped crate being also adapted to lie upon the bed frame when lowered to provide supporting slats for seat cushions or the like, with the last mentioned section resting inclined upon the parallel movement bar to serve as a head support for pillows and the like; a table having legs on one side only thereof, said legs being pivotally connected to the upper end and foot of the bed frame whereby the top of 70 said table may project above the bed frame when lowered to form a foot rest and table, said table top forming a cover for the crate when the device is in a folded position; and a support pivotally mounted upon the table 75 on the side opposite the legs, said support depending against the inside of the first mentioned crate section thereby forming a compartment with said crate to receive baggage, and adapted to project above the table top when the bed is lowered to form a support for a shelter or the like.

In witness whereof I hereunto set my signature.

JAMES F. LONG.
